UNITED STATES PATENT OFFICE.

ALEXANDER G. DUNCAN, OF JOLIET, ILLINOIS.

STILL.

1,116,578.

Specification of Letters Patent.

Patented Nov. 10, 1914.

Application filed June 16, 1913. Serial No. 773,941.

To all whom it may concern:

Be it known that I, ALEXANDER G. DUNCAN, a citizen of the United States, residing at Joliet, in the county of Will and State of Illinois, have invented certain new and useful Improvements in Stills, of which the following is a specification.

My invention relates to stills, and refers particularly, though not exclusively, to stills which are used for the purpose of abstracting ammonia from ammoniacal liquors.

My invention is especially useful for the purification of gas generated by by-product coke ovens. In the process of coking coal it is well known that a rich gas is driven off from the coal, this gas containing a considerable percentage of ammonia. The gas is scrubbed in order to free it from various impurities, and the water used for the scrubbing operation absorbs a large quantity of the gaseous ammonia. This solution is then heated with steam in a still so that the ammonia is driven off, then condensed, and used for various well known purposes in the arts.

The stills heretofore in use have been open to various objections. They have usually been constructed with a plurality of horizontally-disposed partitions, each of which contains one or more gas (steam) inlet openings suitably covered by bells or hoods, and also one or more liquid outlet openings. The liquor from which the ammonia is to be extracted is introduced at the top of the still and passes downwardly from one horizontal partition to another. At the same time steam is introduced at the bottom of the still and passes upwardly through the belled gas inlet openings in the various partitions. This steam forces its way through the liquid surrounding the bells, and serves to heat the liquid, thereby expelling ammonia, which passes upwardly with the steam.

It is the object of my invention to overcome the various difficulties above mentioned, and I accomplish this result by constructing each of the horizontally disposed partitions so that the ammoniacal liquor is obliged to flow in a substantially straight path from one side of the partition to the opposite side thereof, thus always presenting fresh liquor to the action of the steam coming through the belled gas inlet openings.

In carrying out my invention I employ a special construction of bell, which will be described hereafter, by which each bell is

securely held in position but may readily be removed. In order to obtain ready access to the bells and various other interior parts of the still, I also provide openings in the sides of the still, these openings being normally sealed by suitable closures.

These and other objects of my invention will be more readily understood by reference to the accompanying drawings, which show a preferred embodiment of my improvements, and in which—

Figure 1 is a side elevation and partial vertical section through my improved still; Fig. 2 is a fragmentary vertical section through a portion of my still, this section being taken at a right-angle to that shown in Fig. 1; and Fig. 3 is a fragmentary plan of one of the sections of which my still is composed.

The still is provided with a base 10, having therein a steam inlet opening 11 and a waste liquor outlet 12. Supported on the base 10 and extending upwardly therefrom are a plurality of still sections 13. One of the sections 14 of which the still is composed is of special construction, the purpose of which will be described hereafter. Each of the still sections 13 is provided with the flanges 15 by means of which it is fastened by bolts or otherwise to the adjacent sections. In the side walls of each section 13 are apertures 16 which are normally closed by the closures 17. The closures 17, however, may readily be removed in order to give access to the inside of the still section.

As most clearly shown in Figs. 2 and 3, each of the still sections is preferably square or rectangular, and is provided with one or more gas inlet openings 18 which are bounded by the upstanding flanges 19. Each of the openings 18 is preferably in the form of a long and narrow slot, and is covered with the bell 20, which extends downwardly over the flange 19. The bell 20 is provided with supporting lugs 21, but a space 22 is left between the flange 19 and the downwardly-extending flange 23 of each bell as best shown in Fig. 3. At one end, each of the bells 20 engages an obliquely-disposed locking surface 24 preferably formed integral with the sealing wall 25. The opposite end of each bell is held in position by the wedge 26, which engages the obliquely-disposed surface 27 of the web 28 on one side and the end of the bell on the opposite side.

The horizontally-disposed partition 28 of

each of the still sections 13 has toward one side thereof the sealing wall 25 previously mentioned, and toward the opposite side the damming wall 29, connected with the side 5 wall of the section by the webs 29*. Immediately adjacent to the damming wall 29 is the outlet opening 30, which preferably extends completely across one side of each still section 13.

10 On the side of the still section at which the sealing wall 25 is located there is also a sealing wall 31 connected to the side of the still section by the webs 32, thus forming an inlet opening or slot 33.

15 In assembling the still the still sections 13 are so placed that the outlet opening 30 of one section registers with the inlet opening 33 of the section next below.

The still section 14 previously mentioned 20 is preferably of somewhat greater height than the other still sections 13 of which the still is constructed. It is provided with the gas inlet openings 34 and the bells 35 of similar construction to those used in connection with the other still sections but 25 preferably somewhat larger. This section is provided with a conduit 36 having the inlet opening 37 which registers with the outlet opening 30 of the still section 13 immediately 30 above the still section 14. The conduit 36 leads to a lime tank, such as is usually employed in connection with ammonia stills, and is of well known construction. A pipe 38 is also adapted for connection 35 with the lime tank and serves to conduct liquid therefrom to the still section 14 through the opening 39 in the latter.

The uppermost still section 13 has communicating therewith the pipe 40, which 40 introduces to the still section the liquor from which ammonia is to be extracted. This uppermost section is covered by the cap 41 having the outlet 42, which preferably communicates with an ammonia condenser.

Having thus described the construction of my improved still, its operation may now be readily understood. The ammoniacal liquor is first introduced to the upper still 50 section 13 through the pipe 40. The liquor rises in the left-hand portion of this section (indicated in Fig. 2) until it is at a level with the upper edge of the sealing wall 25. The liquor then overflows this sealing wall 55 and passes to the right over the surface of the partition 28 until it reaches the damming wall 29. The liquor rises until it reaches the upper edge of the damming wall and then overflows and passes into the 60 liquid outlet opening 30. It will be evident that the level of liquor maintained in the still section 13 will be of the height of the upper edge of the damming wall 29. The lower edge of the flange 23 of the bell 20 65 being below the level of the liquor, any

steam or gas passing upwardly through the openings 18 must pass through the liquor contained in the still section. The liquor passing through the outlet opening 30 flows downwardly through the inlet opening 33 70 into the next lower still section 13, this liquor rising until it reaches the upper edge of the sealing wall 25. The lower edge of the sealing wall 31 is at a lower level than the upper edge of the sealing wall 25, thereby preventing the passage of gas from the interior of the still section to the liquid outlet opening 30 of the next higher section. The liquor then flows through successive still sections 13 in the manner first 75 described in connection with the upper section. The liquor entering the opening 37 of the conduit 36 in the still section 14 passes to the lime tank in the manner previously described, where the liquor, as is well known, 80 is subjected to heat, which serves to facilitate the expulsion of ammonia from the ammoniacal liquor. The liquor mixed with a certain percentage of lime returns to the still section 14, through the pipe 38 and the 85 opening 39, passes through the outlet opening 30 of this section, and then passes successively through the still sections 13 below the section 14, in the manner previously described. The liquor finally passes out 90 through the waste liquor outlet 12 in the base of the still. 95

While the liquor is flowing through the still in the manner just described, the steam introduced through the steam inlet 11 passes 100 upwardly through the openings 18 in the lowermost still section 13. These openings 18 preferably have their axes at substantially a right-angle to the axes of the openings 30 and 33. By the action of the bells 105 20 this steam is forced through the ammoniacal liquor adjacent to said bells, and serves to heat said liquor, thereby expelling ammonia therefrom, this gaseous ammonia passing upwardly with the steam. On account of the flow of the liquor from one side of each still section to the other, fresh liquor is constantly presented for the action of the steam, and for this reason the expulsion of ammonia in my still is very efficiently performed. As previously described, the steam passing upwardly and carrying ammonia with it can only pass through the gas inlet openings 18 on account of the fact that the liquid inlet openings 33 are efficiently sealed 115 by the joint action of the sealing walls 25 and 31. The steam and ammonia after reaching the uppermost still section 13 pass into the outlet conduit 42, and thence to an ammonia condenser. 120

When it is desired to remove one of the bells 20 it is only necessary to first remove one of the closures 17, then withdraw the wedge 26, after which the bell may readily be withdrawn from its engagement with the 130

locking surface 24, and may be removed through the opening 16.

It will be apparent to those skilled in the art that many changes could be made in the exact type of still which I have described without departing from the spirit or scope of my invention.

What I claim is:

1. In a still, the combination of a plurality of still sections one above another, each section comprising a horizontally-disposed partition having a liquid outlet opening at one side and a damming wall adjacent said opening, a sealing wall spaced apart from the side wall of said section on the side opposite said outlet opening and having its lower edge clear of said partition, thereby forming a liquid inlet opening, the liquid inlet opening of each section registering with the liquid outlet opening of the section next above, and a second sealing wall extending upwardly from the partition of each of said sections in proximity to said first sealing wall and having its upper edge on a higher level than the lower edge of the first sealing wall, whereby a liquid seal is formed by the liquid passing into each section through said liquid inlet opening, substantially as described.
2. In a still, the combination of a plurality of substantially rectangular still sections one above another, each section comprising a horizontally-disposed partition having an elongated liquid outlet opening at one side thereof and a damming wall adjacent said opening, a sealing wall spaced apart from and of substantially the same length as the side wall of said section on the side opposite said outlet opening and having its lower edge clear of said partition, thereby forming an elongated liquid inlet opening, the liquid inlet opening of each section registering with the liquid outlet opening of the section next above, and a second sealing wall extending upwardly from the partition of each of said sections, said second sealing wall being substantially parallel with said first sealing wall and located nearer to the liquid outlet opening of said section, the upper edge of said second sealing wall being at a higher level than the lower edge of the first sealing wall, whereby a liquid seal will be formed when liquid flows into said section through said inlet liquid opening, substantially as described.
3. In a still, the combination of a plurality of still sections one above another, each section comprising a horizontally-disposed partition having a liquid outlet opening toward one side and a gas inlet opening, a damming wall adjacent said liquid outlet opening, a sealing wall spaced apart from the side wall of said section on the side opposite said outlet opening and having its lower edge clear of said partition, there-

by forming a liquid inlet opening, the liquid inlet opening of each section registering with the liquid outlet opening of the section next above, and a second sealing wall extending upwardly from the partition of each of said sections in proximity to said first sealing wall and having its upper edge on a higher level than the lower edge of the first sealing wall, whereby a liquid seal is formed by the liquid passing into each section through said liquid inlet opening, substantially as described.

4. In a still, the combination of a plurality of substantially rectangular still sections one above another, each section comprising a horizontally-disposed partition having an elongated liquid outlet opening at one side thereof and an elongated gas inlet opening having its axis at substantially a right-angle to the axis of said liquid outlet opening, a damming wall adjacent said liquid outlet opening, whereby the liquid in said section may be maintained at a predetermined height, means for forcing gas introduced through said inlet opening through the liquid in said section, a sealing wall spaced apart from and of substantially the same length as the side wall of said section on the side opposite said outlet opening, the lower edge of said sealing wall being clear of said partition, thereby forming an elongated liquid inlet opening, the liquid inlet opening of each section registering with the liquid outlet opening of the section next above, and a second sealing wall extending upwardly from the partition of each of said sections, said second sealing wall being substantially parallel with said first sealing wall and located nearer to the liquid outlet opening of said section, the upper edge of said second sealing wall being at a higher level than the lower edge of the first sealing wall, whereby a liquid seal will be formed when liquid flows into said section through said liquid inlet opening, substantially as described.

5. In a still, the combination of a plurality of still sections one above another, each section having a horizontally-disposed partition with a gas inlet opening therethrough, an upwardly extending flange surrounding said opening, a bell having its lower edge on a level lower than the upper edge of said flange, and readily removable wedge means for holding said bell in position, substantially as described.

6. In a still, the combination of a plurality of substantially rectangular still sections one above another, each section comprising a horizontally-disposed partition having an elongated gas inlet opening therein, an upwardly extending flange surrounding said opening, a bell above said opening, the lower edge of said bell extending to a lower level than the upper edge of said flange, locking

means on said partition engaged by one end of said bell, and readily removable wedge means for securing the opposite end of said bell to said partition, substantially as described.

7. In a still, the combination of a plurality of substantially rectangular still sections one above another, each section having an opening in its side wall, readily removable means for closing said opening, each of said sections comprising a horizontally-disposed partition having an elongated gas inlet opening therein, an upwardly extending flange

surrounding said opening, a bell above said opening, the lower edge of said bell extending to a lower level than the upper edge of said flange, locking means on said partition engaged by one end of said bell, and readily removable wedge means for securing the opposite end of said bell to said partition, substantially as described.

ALEXANDER G. DUNCAN.
